(57) **CLAIM**

The ornamental design for a curved tabletop mirror with embedded discrete border lighting as shown and described.

DESCRIPTION

FIG. 1 is a front perspective view for a first embodiment of the curved tabletop mirror with embedded discrete border lighting;

FIG. 2 is a bottom view of the first embodiment;

FIG. 3 is a front view of the first embodiment;

FIG. 4 is a left view of the first embodiment;

FIG. 5 is a right view of the first embodiment;

FIG. 6 is a back view of the first embodiment;

FIG. 7 is a top view of the first embodiment;

FIG. 8 is a front perspective view for a second embodiment of the curved tabletop mirror with embedded discrete border lighting;

FIG. 9 is a bottom view of the second embodiment;

FIG. 10 is a front view of the second embodiment;

FIG. 11 is a left view of the second embodiment;

FIG. 12 is a right view of the second embodiment;

FIG. 13 is a back view of the second embodiment;

FIG. 14 is a top view of the second embodiment;

FIG. 15 is a front perspective view for a third embodiment of the curved tabletop mirror with embedded discrete border lighting;

FIG. 16 is a bottom view of the third embodiment;

FIG. 17 is a front view of the third embodiment;

FIG. 18 is a left view of the third embodiment;

FIG. 19 is a right view of the third embodiment;

FIG. 20 is a back view of the third embodiment;

FIG. 21 is a top view of the third embodiment;

FIG. 22 is a front perspective view for a fourth embodiment of the curved tabletop mirror with embedded discrete border lighting;

FIG. 23 is a bottom view of the fourth embodiment;

FIG. 24 is a front view of the fourth embodiment;

(Continued)

FIG. 25 is a left view of the fourth embodiment;
FIG. 26 is a right view of the fourth embodiment;
FIG. 27 is a back view of the fourth embodiment; and,
FIG. 28 is a top view of the fourth embodiment.
